CLAIM

The ornamental designs for an overdose resistant drug delivery syringe, as shown and described.

DESCRIPTION

FIG. 1 is a perspective view of an embodiment of a design for an overdose resistant drug delivery syringe;

FIG. 2 is a front view of the overdose resistant drug delivery syringe illustrated in FIG. 1;

FIG. 3 is a back view of the overdose resistant drug delivery syringe illustrated in FIG. 1;

FIG. 4 is a first side view of the overdose resistant drug delivery syringe illustrated in FIG. 1;

FIG. 5 is a second side view of the overdose resistant drug delivery syringe illustrated in FIG. 1;

FIG. 6 is a top view of the overdose resistant drug delivery syringe illustrated in FIG. 1; and,

FIG. 7 is a bottom view of the overdose resistant drug delivery syringe illustrated in FIG. 1.

The broken lines in the figures show portions of the overdose resistant drug delivery syringe that form no part of the claimed design.
